CLAIM

The ornamental design for a condiment dispensing cap with closure or similar article, as shown and described.

DESCRIPTION

FIG. 1 is a perspective view of a condiment dispensing cap with closure or similar article showing my new design, the bottle shown in broken lines for illustrative purposes only;

FIG. 2 is a side elevational view thereof;

FIG. 3 is a top plan view thereof;

FIG. 4 is a bottom plan view thereof;

FIG. 5 is a side elevational view thereof with the closure removed for illustrative purposes;

FIG. 6 is a top plan view of FIG. 5; and

FIG. 7 is a cross-sectional view taken along line 7—7 of FIG. 3.

FIG. 1

FIG. 2

FIG. 3

FIG. 6

FIG. 4

FIG. 5

FIG. 7
